UNITED STATES PATENT OFFICE.

HARRY S. STERNBERGH, OF DETROIT, MICHIGAN, ASSIGNOR TO W. W. BLAKELY, OF DETROIT, MICHIGAN.

HOLD-DOWN DEVICE.

Application filed December 7, 1925. Serial No. 73,789.

This invention relates generally to devices for holding vehicles and the like against movement during shipment and refers more particularly to the means for anchoring such devices upon the floors of 5 freight cars or other suitable carriers.

One of the essential objects of the invention is to provide a connection between the 10 loop portion or tie member of the device and its anchorage means that will prevent the securing elements from ripping either part when the device is subjected to strains and stresses.

Another object is to provide a device of 15 this character that is simple in construction and can be manufactured at a comparatively low cost.

With the above and other objects in view, the invention resides in certain novel features of construction, combinations and arrangements of parts as will be more fully pointed out in the appended claims.

In the accompanying drawing:

Figure 1 is a side elevation of a device 25 embodying my invention applied to a vehicle.

Figure 2 is a perspective view of the device.

Referring now to the drawing, the number 1 designates a device embodying my 30 invention for holding a vehicle upon the floor of a freight car while in transit. As shown, this device is preferably in the form of an inverted U-shaped loop 2 having at 35 its free ends the lateral foot portions 3 to which the anchor plates 4 are preferably secured. Both the loop 2 and plates 4 are preferably constructed of band iron and are provided with suitable openings 5 for 40 receiving securing elements such as the nails 6. Inasmuch as the anchor plates 4 cross the foot portions 3, an opening 5' in each plate is preferably placed in registration with a similar opening in each foot portion 45 3 so that one of the nails 6 may be driven through both the foot portion and plate. To insure a permanent connection between the loop 2 and plates 4, the latter are preferably welded to the foot portions 3 at points 50 8 and 9, respectively, on a transverse line located preferably between the registering openings and the upright leg portions 7 of the loop. Inasmuch as the welding is located at these points the full strength of 55 the metal will be obtained to resist strains

and stresses to which the assembled parts may be subjected. This is a very important factor to be considered especially in devices of this kind, for it is apparent that the openings necessarily weaken the band iron 60 and would cause breaks if the welds were not at the points shown. For instance, if the welds were located between the registering openings and the outer ends of the foot portions 3, it would be apparent that 65 the full strength of the metal could not be drawn upwardly and inwardly by the loop portion 2 and have a tendency to separate from the foot portions 3 at the inner sides of the openings, with the result that the securing elements driven through the registering openings would rip the anchor plates and thereby render the device inoperative for the purposes for which it was 70 designed. With applicant's present construction, these objectionable features are overcome entirely by the location of the welds at the inner sides of the registering openings. As a result the welds permit the 75 combined strength of the metal to be obtained before the registering openings are reached, hence the securing elements or nails 80 6 will not rip either the foot portions 3 or the anchor plates 4.

In use, the loop portion 2 straddles a 85 spring, an axle, or other suitable part of the vehicle and the assembled foot portions 3 and anchor plates 4 are fastened to the floor of the carrier by means of the nails 6.

While it is believed that from the foregoing description, the nature and advantage of my invention will be readily apparent, I desire to have it understood that I do not limit myself to what is herein shown and described and that such changes may 90 be resorted to when desired as fall within the scope of what is claimed.

What I claim as my invention is:

1. A device of the class described comprising a tie member having a leg portion, a substantially flat foot portion projecting from the lower end of said leg portion, and a substantially flat anchorage member crossing and welded to said foot portion adjacent to the junction of said foot and leg portions, the welded point being located at the inner edge of said anchorage member and at the inner end of said foot portion, and said anchorage member having lateral extensions 105 projecting beyond opposite sides of said foot 110

- portions and provided with apertures for receiving securing elements.
2. In a device of the class described, the combination with a tie member having an ⁵ upstanding leg portion and a substantially horizontal foot portion, said foot portion being provided with an opening for receiving a securing element, of an anchorage plate having an opening registering with the ¹⁰ opening in the tie member, and a welded connection between said plate and foot portion on a transverse line located between the registering openings and said leg portion.
3. A hold-down device comprising a strap ¹⁵ iron tie member having an upright leg por-

tion and a lateral foot portion, said foot portion being provided with an opening for receiving a securing element, a strap iron anchorage plate crossing the foot portion and having openings therein for receiving ²⁰ securing elements, one of said openings registering with the opening in said foot portion for receiving the first mentioned securing element, and a welded connection between said plate and foot portion on a transverse line located between the registering ²⁵ openings and the leg portion of said tie member.

In testimony whereof I affix my signature.
HARRY S. STERNBERGH.
